(57) **CLAIM**

I claim the ornamental design for a seating unit, as shown and described.

DESCRIPTION

FIG. 1 is a front upper perspective view of a seating unit, showing my new design;

FIG. 2 is a first side elevational view thereof;

FIG. 3 is a second side elevational view thereof, the second side elevational view being opposite the first side elevational view;

FIG. 4 is a front elevational view thereof;

FIG. 5 is a rear elevational view thereof;

FIG. 6 is a top plan view thereof; and,

FIG. 7 is a bottom plan view thereof.

The broken lines are to show portions of the seating unit that form no part of the claimed design.

The seating unit is shown with a symbolic break in its length. The appearance of any portion of the article between the break lines forms no part of the claimed design.
